UNITED STATES PATENT OFFICE.

H. WILLIAM ELLICOTT, OF BALTIMORE, MARYLAND.

SUPERHEATER.

SPECIFICATION forming part of Letters Patent No. 292,292, dated January 22, 1884.

Application filed August 21, 1883. (No model.)

To all whom it may concern:

Be it known that I, H. WILLIAM ELLICOTT, of the city of Baltimore and State of Maryland, have invented certain Improvements in 5 Superheaters, of which the following is a specification.

My invention relates to improved means for producing dry and superheated steam; and it consists in combining with a boiler and 10 its furnace a combustion-chamber, to which the products of imperfect combustion from the tubes or flues of the boiler are discharged and combined with atmospheric air or other elements which will render their combustion 15 complete. Further, I provide a heating-chamber separated from the combustion-chamber by a perforate fire-brick arch or partition, and inclose within the said heating-chamber a pipe or series of pipes, to which steam is admitted 20 from the boiler to be superheated, and from which it is conducted to the engine. These pipes are protected against the direct action 25 of heat by being incased in fire-brick or other refractory material.

25 In the further description of my said invention which follows, reference is made to the accompanying drawings, forming a part hereof, and in which—

Figure I is a longitudinal view, partly in 30 section, of a boiler and furnace to which my improvements are applied; and Fig. II is a sectional plan taken on the dotted line X X, Fig. I.

Similar letters of reference indicate similar 35 parts in both views.

A is the boiler, and B the furnace, which in themselves are of ordinary construction. The furnace has grate-bars *a* and a furnace-door, *b*, as is usual.

40 C is the combustion-chamber, situated, in the present case, in front of the furnace B; and D, the heating-chamber, separated from the combustion-chamber by a perforate arch, *c*.

E is a gang of pipe, or a steam-reservoir, 45 which rests upon the perforate arch *c*, and is connected to the steam-drum of the boiler. The pipe E is covered with some refractory heat-retaining substance, such as fire-brick or fire-clay, and when the former is used the 50 bricks are dovetailed together, or interlocked, to prevent their displacement. The exit-pipe *e* for the superheated steam is shown in dotted lines and only in Fig. II. The combustion-chamber is preferably provided with a

grate, *f*, and a fire-door, *g*, as shown in the 55 drawings, Fig. I, and has apertures for the admission of air. In some cases burners (represented by *h*, Fig. I) are inserted through the wall of the combustion-chamber, and hydrocarbon fluid injected.

Supposing the furnace B to be provided with a bed of fuel on the grate, the operation of the invention is as follows: Smoke and gases from the fuel in the furnace B pass over the bridge-wall to the rear end of the boiler, 60 and return through the tubes or flues to the combustion-chamber C, where they are united with atmospheric air, or with some combustible elements, and consumed, the necessary heat to produce perfect combination of the 65 elements being effected by fuel on the grate *f* of the combustion-chamber, or by burning hydrocarbon fluid, which is introduced to the said chamber through the burners *h*. The heated products of combustion pass to the 70 heating-chamber through the perforate arch or partition *c*, and are brought in contact with the covered pipe E, which contains saturated steam, and change the globules of water into dry steam at a high temperature. 75

From the foregoing it will be understood 80 that with my improved apparatus saturated steam is changed to superheated dry steam by the action of the superheated products of imperfect combustion from the furnace, and 85 after they have been re-enforced by air or any other elements which may be found necessary to render their combustion complete, and that the pipes in which the steam is superheated are protected by the fire-brick casing against 90 the destructive action of gases, &c., at a high temperature.

I claim as my invention—

In combination with a boiler and furnace, 95 a combustion-chamber to which the products of imperfect combustion are introduced, and in which they are combined with other elements to assist in their thorough consumption, a heating-chamber separated from the combustion-chamber by a perforate partition, and 100 a steam-receptacle located in the said heating-chamber and connected by a steam-pipe to the steam-space of the boiler, substantially as specified.

H. WM. ELLICOTT.
